CLAIM

We claim the ornamental design of a waterfowl decoy, as shown and described.

DESCRIPTION

FIG. 1 is a top perspective view of a waterfowl decoy showing an embodiment of the design of the invention.

FIG. 2 is a bottom perspective view thereof.

FIG. 3 is a side elevation view thereof.

FIG. 4 is an opposite side elevation view thereof.

FIG. 5 is an end elevation view thereof.

FIG. 6 is an opposite end elevation view thereof.

FIG. 7 is a top view thereof.

FIG. 8 is a bottom view thereof; and,

FIG. 9 is another perspective view thereof, showing the waterfowl decoy in use. The broken lines shown in this Figure are for illustrative purposes only and form no part of the claimed design.

The broken line showing of structural features in FIG. 9 is included for the purpose of illustrating non-claimed subject matter, and forms no part of the claimed design.
